(57) **CLAIM**

The ornamental design for a bottle with cap, as shown and described.

DESCRIPTION

FIG. 1 is a perspective view of a bottle with cap showing our new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top view thereof;

FIG. 6 is a perspective view showing a second embodiment thereof;

FIG. 7 is a front elevational view of the second embodiment thereof;

FIG. 8 is a left side elevational view of the second embodiment thereof, the right side elevational view being a mirror image thereof;

FIG. 9 is a rear elevational view of the second embodiment thereof; and,

FIG. 10 is a top view of the second embodiment thereof.
